TUNING INDICATOR TUBE

Herbert Nelson, Bloomfield, N. J., assignor, by
mesne assignments, to Radio Corporation of
America, a corporation of Delaware

Application July 31, 1936, Serial No. 93,539

2 Claims. (Cl. 250—27.5)

My invention relates to electron discharge devices, more particularly to such devices useful as visual indicators of voltage and having an electrode which is rendered luminous, and has 5 the appearance of a filament of light which may be of constant height and varying intensity of incandescence and which changes in response to the change in the magnitude of the applied voltage, a device of this character being particularly 10 useful as a tuning indicator in radio receiving sets.

It is an object of my invention to provide an 15 electron discharge device of the kind described, which is particularly suitable for use as a visual tuning indicator in a radio receiving set and in which resonance is indicated by a brilliant luminous glow of an electrode.

In general my invention comprises an envelope 20 having within it a straight filamentary anode and a pair of straight thermionic cathodes positioned on opposite sides of and parallel to said anode. Around each cathode is mounted a straight tubular control electrode parallel to the cathode and having a longitudinal slit opposite and parallel 25 to the filamentary anode and through which electrons from the cathode are projected toward the anode to make it incandescent in response to electron bombardment. In operation the electrons flow from the cathodes to the anode with 30 sufficient velocity to bombard the anode and render it incandescent. The control electrodes are so connected in a radio receiving circuit that when the circuit is tuned to resonance with an incoming signal the filamentary anode becomes 35 incandescent while when the set is not tuned to resonance the anode is dark. The tube is sensitive to small changes in control voltage and in a properly designed circuit the anode can be changed from a dark color to bright incandescence with only a 2 volt change on the control electrodes.

The novel features which I believe to be characteristic of my invention are set forth with particularity in the appended claims, but the invention itself will best be understood by reference 45 to the following description taken in connection with the accompanying drawing in which Figure 1 is a perspective view of an electron discharge device embodying my invention with parts broken away to show details of construction; Figure 2 is an enlarged transverse section taken along line 2—2 of the tube shown in Figure 1; Figure 3 is a transverse section of a modification of Figure 50 2; and Figure 4 shows a circuit arrangement us-

ing a tube made in accordance with my invention.

The electron discharge device or tuning indicator tube shown in Figure 1 comprises an evacuated envelope 10 provided with the usual 5 stem and press 11, and base 12.

In accordance with my invention I mount vertically within the envelope a pair of parallel straight preferably oxide coated filamentary type thermionic cathodes 13 and support them at the 10 lower ends by means of lead and support wires 14 mounted in the press 11, their upper ends by means of springs 15 electrically connected in series through the back support 16 mounted in the glass bead 17, which is in turn supported by 15 the back support 18 mounted on the press 11. Positioned between these cathodes and coextensive with and parallel to the cathodes is the filamentary type anode 19 which receives electrons from the cathodes 13 during operation of 20 the tube. The filamentary anode preferably a fine tungsten wire is supported at its lower end from a lead-in and support wire 20 and at its upper end by a spring 21 attached to the back support 18. Although I specifically show a filamentary type anode a strip of small mass could 25 serve equally as well since it could be heated to incandescence by electron bombardment. To control the flow of electrons from the filamentary cathodes 13 to the anode 19 I provide around each cathode a tubular control member 22 preferably of sheet metal provided with a slot or openings 23 parallel to and opposite the anode 19. The electrons from the cathodes 13 pass through the slots 23 to the anode 19. These control electrodes are supported at their lower end by means of a metal collar 24 supported in turn by the support rods 25 mounted in the press 11. While I show a pair of cathodes and control electrodes, 30 a single cathode and control electrode can be used. The upper end of the electrode assembly 35 may be properly spaced by means of the mica spacer 26.

In operation the voltage applied to the control 45 electrodes 22, determines the intensity of incandescence of the anode 19. The less negative this control electrode 22 is biased with respect to the cathodes 13, the brighter will be the incandescent portion of the anode 19, inasmuch as more electrons from the cathodes reach the anode than when the negative bias on the control electrode is large the electrons reaching the anode are fewer and the anode is dull red or dark. In this embodiment of my invention the incandescent por- 50 55

tion of the voltage or tuning indicator may be viewed from the side of the tube with ease.

Referring to Figure 2, which shows a transverse section of the tuning indicator shown in Figure 1, the control electrodes 22, are so biased that when no signal is being received the voltage difference between the control electrodes 22, and the cathodes 13, is such that the anode is dark, that is the relatively high negative potential on the control electrodes or cylinders permits few if any electrons to get through the slots 23 to the anode 19. As the set is tuned to resonance the voltage difference between the cathodes and the electrodes becomes less, so that the control effect of the electrodes 22 on the electrons leaving the cathodes 13 is less, permitting more electrons from the cathodes 13 to reach the anode 19, so that when the set is tuned to resonance the anode is incandescent and easily seen.

20 The application of an electron discharge device made in accordance with my invention to a radio circuit is shown in Figure 4. Normally the cathodes 13, heated by battery 29, are electrically connected through a biasing battery 30, 25 to one side of a load resistor 31, the voltage across which is to be measured and which may for example be in the a.—v.—c. portion of the circuit. The control electrodes 22 are connected to the other side of the resistor 31. The anode voltage is 30 supplied by battery 32. With no voltage on the control electrodes 22, very few electrons and hence very little current flows through the tube between the cathodes and anodes due to the biasing voltage on the control electrodes 22 and 35 the anode is dark. Any voltage drop across resistor 31 is in opposition to the biasing battery 30. As the voltage drop across resistor 31 increases when the set is tuned to resonance the effective biasing voltage on the control electrodes 22 decreases. Under these circumstances 40 the control electrodes 22 become less negative with respect to the cathodes 13, and more electrons go through the slots 23 to the anode. Thus the anode becomes incandescent as the negative 45 bias on the control electrodes 22 decreases. This characteristic of the tuning indicator tube is made use of when connected for example to a conventional automatic volume control circuit in which resistor 31 may be placed.

50 In the modification shown in Figure 3 the control electrode 27 comprises two conducting cylinders

indical members surrounding the cathodes 13 and joined at the back to provide a background against which anode 19 can be viewed. The control electrode is in effect a tubular member having separate chambers around each cathode, 5 each chamber having a longitudinal opening parallel and opposite to the anode for permitting electrons to reach the anodes, and a longitudinal opening in the side wall through which the anode 10 can be viewed.

While I have indicated the preferred embodiment of my invention of which I am now aware and have also indicated only one specific application for which my invention may be employed, it will be apparent that my invention is by no 15 means limited to the exact forms illustrated or the use indicated, but that many variations may be made in the particular structure used and the purpose for which it is employed without departing from the scope of my invention as set forth 20 in the appended claims.

What I claim as new is:

1. An electron discharge device having an envelope, a pair of straight parallel thermionic cathodes within the envelope for emitting electrons, a straight filamentary anode positioned between and parallel to said cathodes for receiving electrons from said cathodes, and a control electrode for each cathode and comprising a tubular conductor partially surrounding the 25 cathode and having parallel to the cathode and opposite the anode an opening through which electrons reach the anode.

2. An electron discharge device having an envelope, a pair of parallel straight thermionic cathodes within said envelope for emitting electrons, a straight filamentary anode between and parallel to the cathodes, and coextensive therewith, and a control electrode for said cathodes comprising a tubular electrode of sheet metal 30 partially surrounding said cathodes and anode, and providing a separate chamber around each cathode, each chamber having parallel and opposite said anode an opening through which electrons can pass from each cathode to said 35 anode, said control electrode having a longitudinal opening in the wall parallel to said anode through which the filamentary anode can be viewed.

HERBERT NELSON. 50
